EDWARD H. GARRIGUES, OF ST. LOUIS, MISSOURI.

Letters Patent No. 87,406, dated March 2, 1869.

IMPROVEMENT IN SPARK-ARRESTERS.

The Schedule referred to in these Letters Patent and making part of the same

To all whom it may concern:

Be it known that I, EDWARD H. GARRIGUES, of St. Louis, in the county of St. Louis, and State of Missouri, have invented a new and useful Improvement in Spark-Extinguisher; and I do hereby declare that the following is a full, clear, and exact description thereof, which will enable those skilled in the art to make and use the same, reference being had to the accompanying drawings, forming part of this specification.

This invention relates to a new and improved device for extinguishing sparks from chimneys and smoke-stacks; and

It consists in forming such chimney or smoke-stack with a perforated sheet or section, which section forms a portion of the stack, or chimney, and in securing to such perforated section a revolving jacket, with wings thereon, whereby the air is allowed to enter the chimney, or stack, through the perforations, and condense the steam which is exhausted into such stack, or chimney, and thereby extinguish the rising sparks, as will be hereinafter more fully described.

Figure 1 represents the smoke-stacks of a steam-boat, or of a steam-engine.

Figure 2 is a cross or horizontal section, through the line *x x* of fig. 1.

Similar letters of reference indicate corresponding parts.

A represents the stack, or chimney.

B is the perforated section; the perforations extending entirely round the stack.

C represents a cylindrical jacket, which is supported by a projecting flange, *d*, but over the flange and the bottom of the jacket there is a loose recessed collar, *e*.

Within the collar, and between the bottom of the jacket C and the collar *d*, friction-rolls, or balls, are placed, as seen in the drawing, at *g*.

F represents wings, more or less in number, on the jacket C.

A portion of the jacket is cut away, so as to expose

a portion of the perforated section B to the atmosphere, (one-fifth of the circumference, more or less,) the balance of the perforated section being covered by the jacket, so that the air is excluded.

The portion of the perforated stack which is exposed by the jacket is seen more distinctly in fig. 2, and marked *h*.

It will be seen that the wings will keep the open part of the jacket *h* facing the strongest current of air, as the drum revolves easily on the friction-rolls beneath it.

The action of the jacket on the stack is similar to that of the ordinary smoke-jack, its position being governed by the strongest current of air.

It is well known that the exhaust steam from the engine on steamboats and locomotives, and frequently in stationary engines, is discharged into the smoke-stack, or chimneys, for the purpose of increasing the draught.

Such steam, by my arrangement, meets the fine jets of air which pass through the perforations in the stack, and is condensed, producing thereby an atmosphere within the stack sufficiently damp to extinguish the sparks which enter the stack, so that if they are forced out by the upward draught, they fall harmless to the ground.

This spark-extinguisher can be applied to all smoke-stacks and chimneys where steam is used, as described, with the greatest advantage, and with entire safety as regards the discharge of sparks from the stack.

I claim as new, and desire to secure by Letters Patent—

The jacket C, with wings F and rollers E, constructed and arranged, with reference to the perforated section B, as herein shown and described.

E. H. GARRIGUES.
